[57] CLAIM

The ornamental design for a portable prefabricated restaurant building, as shown and described.

DESCRIPTION

FIG. 1 is a front perspective view of a portable prefabricated restaurant building embodying our design.

FIG. 2 is a back perspective view of the building shown in FIG. 1.

The end wall of the building which is at the left of FIG. 1 and at the right of FIG. 2 has the same configuration and appearance as the end wall which appears at the right of FIG. 1 and the left of FIG. 2.
